HOLDER FOR AERIAL TOP

Stephen J. Salayka, 103 Berry St., Brooklyn, N.Y.

Filed Mar. 17, 1964, Ser. No. 79,038

Term of patent 14 years

(Cl. D34—15)

FIG. 1 is a view in elevation from a first, outer side of holder for aerial top showing my new design;

FIG. 2 is a view in elevation from the second, inner side of the holder for aerial top;

FIG. 3 is a view in elevation from the rear end of the holder for aerial top;

FIG. 4 is a view in elevation from the front end of the holder for aerial top; and

FIG. 5 is a view in the plan of the holder for aerial top.

I claim:

The ornamental design for a holder for aerial top, as shown.
